DAMPER

Herman Schaaf, Philadelphia, Pa.

Application October 19, 1935, Serial No. 45,759

5 Claims. (Cl. 126—285)

This invention relates to furnace or heater constructions, and is more particularly concerned with the damper mechanism, mountings therefor, and associated control devices.

5 At the present time there is available on the market a well-known type of furnace structure which includes a so-called gas passage in the upper part of the furnace above the firepot, and this gas passage leads to a connection which 10 is connected with a smokestack or other passage through which the smoke is passed.

In this type of furnace construction it has been the practice to locate the damper in this smokestack connection, or at other places in the 15 furnace, and it has also been common practice to associate with the roof or top structure of the furnace a so-called check damper for admitting cold air above the firepot when it is desired to check or deaden the fire.

20 Another feature of this now well-known type of furnace construction with which this invention is concerned, is the fact that it includes a top structure that embodies a lid as an individual element.

25 With the foregoing features which are characteristic of this well-known type of furnace structure in mind, this invention has in view, as an important object, the provision of a furnace structure of the character described which 30 includes damper mechanism that is operatively associated with the gas passage that is disposed directly above the firepot.

35 In carrying out this idea in a practical embodiment, this invention contemplates a unitary damper assembly which is carried by the lid of the furnace top. With this arrangement the damper mechanism and lid may be properly assembled prior to positioning of the lid in the furnace structure, after which the latter operation may be carried out to insure a proper positioning of the damper in a place which effectively controls drafts of air through the firepot.

40 Another important object of the present invention is to provide, in a furnace structure of the character described, a lid which includes a check damper for admitting cold air above the firepot.

45 In furtherance of the idea of having the lid embody a unitary damper assembly, this invention contemplates the location of the check damper in the lid in addition to the other regular damper mechanism.

50 Another important object of the invention is to provide, in a furnace structure of the character described, which includes a lid in the top

thereof, a damper which is hingedly mounted on an axis below the lid, together with means for swinging the damper into various effective positions.

5 More in detail, this invention has, as an important objective, the provision of operating means for the damper, and which operating means include friction devices for maintaining the damper in any adjusted position.

10 Still another object of the present invention is to provide damper mechanism of the character described, a hinged damper for controlling the gas passage of a firepot, together with mechanism for operating the hinged damper, and which mechanism includes suitable indicia for 15 indicating the opened condition of the damper.

15 Various other more detailed objects and advantages will in part become apparent and in part be hereinafter stated as the description of the invention proceeds.

20 The invention, therefore, comprises a furnace structure including a gas passage for the firepot, and a lid in the top of the furnace above the gas passage, and which lid has suspended therefrom a hinged mounting which carries a damper 25 assembly as well as devices for operating the damper to move it into various effective positions. The latter devices also include friction means for maintaining the damper in any adjusted position, as well as indicia for indicating 30 in just what position the damper is. The lid also includes a check damper together with operating means therefor.

25 For a full and more complete understanding of the invention, reference may be had to the following description and accompanying drawings, 35 wherein:

Figure 1 is a side view partly in section and partly in elevation of the furnace embodying 40 damper mechanism made in accordance with the precepts of this invention.

Figure 2 is a detail plan view of the lid which is included in the top structure of the furnace.

Figure 3 is an enlarged detail view in elevation of the lid shown in Figure 2; this view is 45 taken looking in the direction of the arrow marked 3 of Figure 2.

Figure 4 is a detail showing in side elevation of the lid and damper mechanism suspended therefrom, while

50 Figure 5 is a view taken at right angles to that shown at Figure 4, but of the same mechanism.

Figure 6 is an enlarged detail view in perspective of the friction member which maintains the damper in adjusted position, and

Figure 7 is an enlarged detail perspective of the arrow constituting a part of the indicia.

Referring now to the drawings, wherein like reference characters denote corresponding parts, 5 a furnace of the type with which this invention is concerned is referred to generally by the reference character A, and is shown as including a gas passage B which is disposed above the firepot (not shown). The gas passage B opens 10 into a compartment defined by the top structure designated generally C which is formed with an opening at 10 which is circular in formation and which ordinarily is closed by a lid referred to generally by the reference character D. 15 At the rear of the furnace the top structure C may be provided with a connection at E for conductively connecting a smokestack thereto.

In accordance with this invention the various 20 damper mechanisms which are intended as a controlling means for the fire in the furnace A are carried by the lid D which is intended to be installed as a unit with these damper mechanisms attached thereto. After installation, the lid D may be maintained in position by fastening 25 devices indicated at 11.

Depending from the underside of the lid D is a hanger 12 in the form of a bracket having arms 13 which are enlarged at their extremities, 30 as indicated at 14, and the enlarged portions are provided with openings through which extends a shaft 15. Damper members designated 16 and 17 are formed with ears 18, all of which are provided with openings through which the shaft 15 extends. Suitable means for preventing dis- 35 assembly of the shaft 15, hanger arms 13 and ears 18 may be provided in the form of cotter pins, shown at 19.

As illustrated in Figure 5, the hanger 12 may be secured to the underside of the lid D by rivets 40 shown at 20. The lid D is provided with a so-called dome, which is shown at 21 as being made integral with the lid, although the invention is not to be limited in this respect. As shown in Figures 2 and 4, this dome 21 is of a semi- 45 cylindrical construction, and has a front face 22 that is provided with suitable indicia indicated at 23, which serves a purpose to be later described.

The dome 21 also includes a rear wall 24 that 50 is slightly enlarged, as shown at 25, and formed with an opening at 26 which is in alignment with a similar opening 27 formed in the front wall 22. A shaft 28 extends through the openings 26 and 27, and projects a considerable distance 55 beyond the wall 22 where it is provided with operating means in the form of a handwheel 29 that is nonrotatably connected to the shaft in any preferred manner.

Interiorly of the dome 21 a pair of crank arms 60 30 and 31 are nonrotatably affixed to the shaft 28, as by set screws, one of which is indicated at 32. The extremities of the crank arms 30 and 31 are bifurcated, as shown at 33, and received in the bifurcations 33 are the extremities of links 34 65 and 35. As shown in Figure 5, a pin 36 extends through each of the crank arms, and its respective link, the ends of the pin being expanded to assure permanence of the pivotal connection.

As shown clearly in Figures 4 and 5, the damper 70 member 16 is formed with an ear 37 that is provided with an opening through which extends a pin 38 which pin also extends through a similar opening in the extremity of the link 34. Likewise, the damper member 17 is provided with an ear 39 that has an opening through which extends

a pin 40 that also passes through a similar opening in the lower extremity of the link 35.

It is evident that rotation of the shaft 28 under influence of the handwheel 29, will cause a turning of the arms 30 and 31 to assert a pull on 5 the links 34, 35 whereby the damper members 16 and 17 are swung upwardly into a position such as that indicated by the dotted lines in Figure 4.

Referring now more particularly to Figures 5, 10 6, and 7, a friction device for maintaining the dampers in any adjusted position is shown in the form of a friction disk 41 that is carried by 15 a cage 42 that is positioned about the shaft 28, the disk 41 being adapted for frictional engagement with the face 22 of the dome 21.

The cage 42 is provided with a tubular extension at 43 that defines a flanged surface 44 against which abuts one end of a coil spring shown at 45. The other extremity of the coil spring 45 20 bears against a flange 46 that is defined on the handwheel 29 by a tubular extension 47.

Carried by the shaft 28, but interiorly of the cage 42, is a hub member 48 which is non-rotatably affixed to the shaft 28, as by a set 25 screw 49, and this hub member projects through a slot 50 provided in the cage member 42. Extending from the hub member 48 is an indicator or arrow 51 which cooperates with the indicia 23 on the front face 22 of the dome member 21 30 to indicate the position of the dampers.

It is evident that the spring 45 affects the cage 42 to urge the friction disk 41 against the front face 22 of the dome 21 to create sufficient friction to cause the shaft 28 to stay in any position 35 in which it may be adjusted by the turning of the handwheel 29. The frictional effects of the disk 41 are supplemented by the frictional engagement of the crank arm 30 with the rear face of the front wall 22. At the same time that the 40 spring 45 urges the friction disk 41 against the front face of the wall 22, it exerts a pull on the shaft 28 to cause the crank arm 30 to engage the rear wall. This adjustment is carried out by exerting sufficient force to overcome the effect 45 of this friction disk 41.

Referring now to Figures 1 and 2, the lid D is also shown as including a check damper which is referred to by the reference character 52. This check damper 52 cooperates with an opening 50 defined by the outer end of an upraised portion 53 formed on the lid D to either shut off or admit cold air to the interior of the furnace A above the firebox therein.

The check damper 52 may be carried by an 55 arm 54 that is non-rotatably affixed to a shaft 55 that extends through ears 56 formed on the lid D. Suitable hand-operating devices for causing rotation of the shaft 55 to open and close the damper 52 may be provided, although they 60 are not here shown as they do not form a part of this invention.

As shown in Figure 1, the damper members 16 and 17, when in their fully extended position, substantially close the gas passage B, and they 65 may be swung upwardly by the mechanism above described to open this passage to any desired extent.

In the actual assembly of one of the furnaces made in accordance with this invention, all of 70 the damper mechanism hereinbefore described is first assembled on the lid D after which the latter is installed in the opening 10 and securely fastened therein by the fastening devices 11.

A handwheel 29 may now be availed of to op- 75

erate the damper members 16 and 17 as occasion demands, and the effective positions of the latter will always be indicated by the arrow 51 and indicia 23. Whenever it is desired to deaden or 5 check the fire in the furnace A the check damper 52 may be opened by causing rotation of the shaft 55.

While a preferred specific embodiment of the invention is herein set forth, it is to be understood that I am not to be limited to the exact 10 construction illustrated and described, as various modifications of these details may be provided in putting this invention into practice, within the purview of the appended claims.

15 I claim:—

1. Damper mechanism of the character described comprising a lid, a dome carried by the lid, a shaft extending through said dome, a crank arm in the dome carried by the shaft, a link connected to said crank arm, a damper member connected to said link, and means for hingedly mounting the damper member to the underside of the lid.

2. Damper mechanism of the character described comprising a lid, a dome carried by the lid, a shaft extending through said dome, a crank arm in the dome carried by the shaft, a link connected to said crank arm, a damper member connected to said link, means for 25 hingedly mounting the damper member in operative position, said last mentioned means consisting of a bracket carried by the lid on the underside thereof together with a shaft extending through the arms of the bracket, and ears 30 on the damper.

3. Damper mechanism of the character described comprising a lid formed with a dome, a bracket carried on the underside of the lid, damper members hingedly carried by the bracket, links connected to each of said damper members, crank arms connected to each of said links, a shaft extending through the dome and carrying the crank arms in the dome, and indicia 5 means associated with said shaft and dome for indicating the positions of the dampers. 10

4. Damper mechanism of the character described comprising a lid formed with a dome, a bracket carried on the underside of the lid, damper members hingedly carried by the bracket, links connected to each of said damper members, crank arms connected to each of said links, a shaft extending through the dome and carrying the crank arms in the dome, an operating member for said shaft, and friction devices for 15 maintaining the dampers in adjusted positions. 20

5. Damper mechanism of the character described comprising a lid formed with a dome, a bracket carried on the underside of the lid, damper members hingedly carried by the bracket, links connected to each of said damper members, crank arms connected to each of said links, a shaft extending through the dome and carrying the crank arms in the dome, an operating member for said shaft, friction devices for 25 maintaining the dampers in adjusted positions, said 30 friction devices consisting of a friction disk bearing against the outer face of the dome, and a spring interposed between the friction disk and the operating member.

HERMAN SCHAAF. 35
